DESIGN FOR A DOLL

Leon Goodman, Atlantic City, N. J.

Application March 23, 1948, Serial No. 145,279

Term of patent 3½ years

(Cl. D34—4)

To all whom it may concern:

Be it known that I, Leon Goodman, a citizen of the United States, residing in Atlantic City, State of New Jersey, have invented a new, original, and ornamental Design for a Doll, of which the following is a specification, reference being had to the accompanying drawing forming part thereof, in which—

Fig. 2 is a rear view; and Fig. 3 is a side view on a reduced scale.

I claim:

The ornamental design for a doll, as shown.
LEON GOODMAN.
